COVER FOR AN AQUARIUM FILTER

Vivian C. Orensten, 8724 Westmoreland Lane,
St. Louis Park, Minneapolis, Minn. 55426

Filed Sept. 15, 1975, Ser. No. 613,329

Term of patent 14 years

Int. Cl. D23—01

U.S. Cl. D23—4

FIG. 1

FIG. 3

FIG. 2

FIG. 4

FIG. 5

FIG. 1 is a perspective view taken from the top, one side and one end of a cover for an aquarium filter showing my new design;

FIG. 2 is an elevational view taken from the side opposite that shown in FIG. 1;

FIG. 3 is an end elevational view taken from the left of FIG. 2;

FIG. 4 is an end elevational view taken from the right of FIG. 2; and

FIG. 5 is a top plan view thereof.

What is claimed is:

The ornamental design for a cover for an aquarium filter, as shown.
